UNITED STATES PATENT OFFICE.

OSCAR M. NELSON, OF NEW ORLEANS, LOUISIANA.

CLARIFIER.

Application filed April 11, 1919. Serial No. 289,462.

To all whom it may concern:

Be it known that I, OSCAR M. NELSON, a citizen of the United States, residing at New Orleans, in the parish of Orleans and State 5 of Louisiana, have invented new and useful Improvements in Clarifiers, of which the following is a specification.

It is the object of the invention, among other things, to provide a mechanism of 10 simple structure, so designed and constructed that the heavier foreign substances in the juices or syrups will accumulate upon the bottom and be readily removed therefrom, and not interfere with the continuous boiling 15 operations, and means for supplying the required heat at a point sufficiently distant from said bottom to permit the boiling process to continue without agitating the precipitates on said bottom; to facilitate the 20 upward movement of the boiling juices by a limited pressure thereon derived from the juices, and provide means for insuring a circulation of the juices about the axis of the device as well as in a vertical plane.

To these and other ends my invention 25 consists in the clarifier having certain details of construction and combinations of parts as will be hereinafter described and more particularly pointed out in the claim.

Referring to the drawings in which like numerals of reference designate like parts in the several figures;

Figure 1, is a plan view of my improved clarifier; and

Figure 2, is a vertical section thereof partly in side elevation.

In the practice of my invention I provide a pan 1 having a cylindrical wall 3 terminating in an outwardly flaring flange 2 at its 40 top end and closed at its lower end by a conical bottom formed by the walls 9 and 10, at the peak of which is a discharge pipe 17 suitably valved. The juices are admitted into this pan through the intake pipe A and discharged therefrom through the exhaust pipe 6 or other convenient means. This exhaust pipe having a head 8 thereon is attached by means of the connection 7, or other conventional means, to that portion of the 45 cylindrical wall 3 that is designated 4. Supported within the pan 1 is a hollow drum 12 having top and bottom plates 11, which support the opposite ends of the tubes 13.

The outside diameter of this drum 12 is 50 of such relative size that the open space be-

tween the outside thereof and the inside of the cylindrical wall 3 is of greater cross-sectional area than that of the combined cross-sectional areas of all of the openings in the tubes 13.

Steam is admitted to the drum 12 through the pipe 14 secured thereto by the collar 15, and exhausted therefrom through the pipe 22 secured by a flange 16 or other preferred means, elbow 26 and offset pipe 27 that extends through the wall 3 and supported thereat by the flange or collar 19. To prevent the steam passing directly through the drum in a straight line from the pipe 14 to the pipe 22, I have provided a baffle plate 5 70 within the drum that deflects the steam radially and distributes it throughout the drum 12 and around all of the tubes 13.

If it is desired that the juices travel in a circuitous path within the pan, this may be 75 accomplished through the medium of two or more baffle plates 21, which may be inserted within the pan so that one end of each is substantially flush with the outer edge of the drum 12, and the opposite end 80 substantially in contact with the inner face of the wall 3, as shown in Figure 1 wherein they are shown as being arranged parallel with each other. The drum 12 is supported by the baffle plates which project thereunder 85 at one end. A different number and arrangement of plates may be adapted and operate equally as well as the two plates herein shown.

The steam due to baffle 5 effects more uniform heating of the tubes 13 and by the described arrangement of the baffles 21 and 21, the juices are initially caused to flow along the part of the drum adjacent to pipe A, then between the two baffles 21, where the 95 juices encounter the hottest area of the drum, and finally the juices will flow along the outer side of the baffle 21 adjacent to the pipe 6. The juices are thus brought into heating contact with the entire drum and 100 the heat of the latter is imparted to the juices in an efficient and thorough manner so that the heat of the drum is utilized to the greatest possible extent. Otherwise stated, the juices must encounter not only, 105 the hottest parts of the drum but all parts thereof in their travel from inlet A to outlet 6.

Such air as may accumulate in the drum 12 is permitted to escape therefrom through 110

the vents 20, two of which are shown in the drawing, but a greater or less number may be used, if desired.

In practice, the pans 1 may be arranged in series with the juices or syrups passing successively from one to the other, being admitted through an intake pipe A or other similar means and discharged through an exhaust pipe 6 or similar means.

- 10 In operation, the juices in the pan adjacent to the drum are first subjected to the heat therein and consequently move upwardly through the tubes 13 from the underside of the drum to the top thereof in a plurality of streams that bubble over and flow outwardly over the top of said drum. The juices then move downwardly through the open space between the outside of the drum and the inside of the cylindrical wall 20 3. The boiling operation is thus continuous, the boiling juices rising through the tubes 13 and then flowing downwardly between the drum and wall 3 and again passing upwardly through said tubes 13. The juices 25 as they rise and fall in boiling progress along the circuitous path about the vertical baffles from inlet A to outlet 6.

As the volume of juices surrounding the drum is greater than that of the upwardly moving juices, a pressure is created upon the juices underneath the drum that facilitates and accelerates the speed of the juices moving upwardly through the tubes. By this action the juice particles are moving at varying speeds and as a result thereof, the action of one upon the other has a tendency to destroy and break up these particles and thus relieve the foreign substances therein. The lighter of these foreign substances rise 30 to the surface of the juices and are removed by skimming processes, while the heavier substances are precipitated to the bottom of the pan where they accumulate and are drawn off through the discharge pipe 17. 40 45 The conical bottom of the pan facilitates this action and as the distance between it

and the underside of the drum 12 is so relatively great, these heavier substances having been once freed from the juices fall to the bottom and do not travel upwardly with the boiling juices, as there is a sufficient volume of juices passing above the sediment on the bottom of the pan to continue the operations, without disturbing or agitating it.

The operation of clarifying sugar juices 55 in my improved device results in the practical elimination of all foreign substances, both light and heavy, without the use of chemicals such as sulphur or lime commonly used heretofore and the same are admitted 60 and discharged adjacent to the top of the pan.

What is claimed is:

In a clarifier, a pan having an inlet and an outlet at opposite sides thereof, a steam 65 drum in the pan spaced from the walls thereof and having a series of vertical pipes extending through the top and bottom thereof, an inlet and an outlet for the drum oppositely disposed and arranged at the center 70 thereof, a baffle between the inlet and outlet of the drum spaced from the inlet and disposed adjacent thereto to effect lateral movement of the incoming steam against the tubes and toward the drum periphery, vertically 75 disposed baffles one of which extends from a side wall of the pan and between the inlet thereof and the center of the pan and across the drum and spaced from the opposite side wall of the pan and a second of which extends between the outlet of the pan and the center of the pan and from said opposite side wall and across the drum and spaced from the first named side wall of the pan.

In testimony whereof I have hereunto set 80 my hand in presence of two subscribing witnesses.

OSCAR M. NELSON.
